MECHANISM FOR STRETCHING FUR
SCARVES AND PELTS

Erme Kuznetsof, Brooklyn, N. Y.

Application August 17, 1942, Serial No. 455,149

5 Claims. (Cl. 45—24)

This invention relates to improvements in a mechanism for stretching fur scarves and pelts, and it consists in the novel features which are hereinafter described.

One of the objects of my invention is to provide a mechanical means for increasing the length of a fur scarf or pelt, either raw or finished, beyond the limit which may be attained by hand stretching as at present.

Another object is to have the fur scarf or pelt clamped at one of its ends and fastened at its other end to one end of a bar and thereupon to apply an intensified force to the other end of the bar and provide a means to prevent overhauling of the said force, whereby to stretch the pelt or the fur scarf to a permanent elongation of the same.

A further object is to improve the quality of the fur by the above described process.

A still other object is to have my mechanism for stretching fur scarves and pelts relatively simple, compact, durable and inexpensive.

Other objects and advantages will hereinafter appear.

I attain these objects by the mechanism which is illustrated in the accompanying drawing or by any mechanical equivalent or obvious modification of the same.

In the drawing Fig. 1 is a fragmentary longitudinal vertical section of my mechanism, showing some parts in elevation; Fig. 2 is a cross-section on the line 2—2 of Fig. 1, looking in the direction of the arrows; Fig. 3 is a cross-section on the line 3—3 of Fig. 1, looking in the direction of the arrows; and Fig. 4 is a sectional plan on the line 4—4 of Fig. 2, looking in the direction of the arrows, drawn to a smaller scale than the other figures of the drawing.

Fig. 5 is a detail in front elevation, looking from left to right in Fig. 1, of a pusher block which is hereinafter described, and Fig. 6 is a top view of the same.

Similar numerals refer to similar parts throughout the several views.

11 designates a stretcher bar to the rear end of which is attached the rear end of a sleeve-like fur scarf or pelt 12, which is turned inside out, by means of suitable fastenings, such as nails as at 12a in Fig. 4.

The front end or head 32 of the scarf or pelt 12 is placed between the base 33 and cap 34 of a clamp 33—34, as shown in Fig. 1, in which the rear end of the stretcher bar 11 with the greater part of the scarf or pelt 12 is broken away.

A yoke 35 is attached to the enlarged middle part of the cap 34 by means of fastenings which are omitted in the drawing, and has attached thereto the lower end of a bolt 36 by means of sleeves 37 and 38 which are secured to the bolt 36 as shown in Figs. 1 and 3; the bolt 36 is threaded as shown.

The bolt 36 passes through an opening in a bridge 39 which is supported by standards 40, and is in engagement with a nut 41 which is mounted on the bridge 39 and is secured thereto.

An arm 42 is secured to the upper end of the bolt 36 and terminates in a pin or handle 43. By turning the bolt 36 in the required direction, by means of the arm 42 and the pin or handle 43, pressure is applied by means of the yoke 35 to the cap 34 of the clamp 33—34, thereby securely holding the head end 32 of the fur scarf or pelt 12 in position.

The ends of the cap 34 fit between two pairs of guides 44 on said standards 40, to prevent rotation of the cap by the bolt 36.

The standards 40 are integral with the rear end of a frame 19—20, which has therein an opening 21 extending to the wall 45 at the front end thereof.

The wall 45 has thereon at the front end thereof integral therewith a bearing 25 for a journal 24, which has secured thereto at the front end thereof an arm 26 which terminates in a pin or handle 26a, and has secured thereto rearwardly of the bearing 25 a sleeve 27, to prevent longitudinal displacement of the journal 24 with relation to the frame 19—20.

The journal 24 has integral therewith and extending rearwardly therefrom a feedscrew 23 which is in engagement with a feed nut 14 which is integral with a pusher block 13, which has therein a cavity or groove 15 and two pairs of flanges 17 and 18, one pair at the top and one pair at the bottom of the block 13.

The pusher block 13 is introduced into the frame 19—20 through enlarged vertical openings 16a in the top 19 and bottom 20 of the frame 19—20 and is normally positioned in slots 16 in the top 19 and bottom 20 of the frame; the slots 16 are narrower than the opening 16a, and they don't allow the flanges 17 and 18 to pass therethrough; the flanges 17 are in sliding contact with the top 19 and the flanges 18 are in sliding contact with the bottom 20 of the frame 19—20.

The stretcher bar 11 extends through an opening 21 between the top 19 and bottom 20 of the frame 19—20 and abuts at the front end 11a

thereof against the front wall 13a of the block 13 at the front end of the groove 15.

The opening 21 is wider than the stretcher bar 11 to provide for bars of different sizes made for scarves or pelts of different widths; and a pair of guides 22 is shown as employed for reducing the width of the space on each side of the bar 11 in the opening 21; guides 22 of different widths may be employed for stretcher bars 11 of different sizes.

The front end of the stretcher bar 11 is shown as tapered at 11a; and the rear ends of the guides 22 are shown also as tapered, to facilitate the assembling of these parts in the opening 21.

By turning the arm 26 by means of the pin or handle 26a in the requisite direction the screw 23 will move the feed nut 14 with the block 13 from right to left in Fig. 1; the front wall 13a of the block 13 will press on the end 11a of the stretcher bar 11 and push the latter rearwardly, thereby stretching the fur scarf or pelt 12 which extends from the clamp 33-34 in Fig. 1 to the point at which it is secured to the stretcher bar at 12a, as shown in Fig. 4; only a very small part of the fur scarf or pelt is shown in Fig. 1, and a larger part is shown in Fig. 4.

When the stretching operation is completed the cap 34 of the clamp 33-34 may be raised by turning the arm 42 in the proper direction, and the head 32 of the fur scarf or pelt is thereby released; the stretcher bar 11-11a may then be removed from the opening 21 of the frame 19-20 and another fur scarf or pelt placed on the stretcher bar 11 to be stretched.

The front wall 45 of the frame has thereon a pair of angular braces 28 for engaging by means of screws 28a the front end of a table or board 29 on which the frame 19-20 is mounted and from which it is spaced by means of spacing blocks or feet 30 and 31 which may be either integral with the frame 19-20 as at 31 or attached thereto.

The blocks or feet 30 and 31 enable the flanges 18 of the pusher block 13 to slide on the bottom 20 of the frame 19-20 without interfering with the table 29.

The screw 23 is not overhauling, the operation of stretching may, therefore, be stopped for a while as for inspection of the condition of the pelt or fur scarf.

The device as shown is operated manually; but, if desired, the arm 26 may be replaced by one or more pulleys and clutches and operated by means of power supplied by a belt or motor.

Instead of the feed nut 14 and bearing 45 a stationary nut may be employed and the screw 23 made to travel longitudinally and push the block 13, which may be made without the nut 14 on it; the sleeve 27 may then be omitted and the screw 23 lowered to the level of the stretcher bar 11.

Other variations are possible, and parts of my invention may be used without other parts.

I do not, therefore, restrict myself to the details as shown in the drawing.

5 I claim as my invention and desire to secure by Letters Patent:

1. In a mechanism for stretching fur scarves lengthwise of the latter a frame having therein a longitudinally centrally extending opening, an 10 elongated stretcher bar having the inner end thereof slidably positioned in said opening, the outer end of said bar being adapted to be encompassed by and to have attached thereto the outer end of a sleeve-like fur scarf, a clamp on the 15 outer end of said frame for detachably connecting thereto the inner end of said fur scarf, and a means on the inner end of said frame for applying an intensified force to the inner end of said bar in a direction lengthwise thereof whereby to stretch said scarf lengthwise of the latter.

2. The elements of claim 1, said force applying means including a pusher block in said opening, in line with said bar, slidably connected to said frame and abutting against the inner end of said bar, and a threaded means at the inner end of said frame for moving the said pusher block in a direction lengthwise of said bar from the inner end towards the outer end of said frame.

3. The elements of claim 1, said force applying means including a pusher block in said opening abutting against the inner end of said bar, slidably connected to said frame, a feed nut integral with said block, to move said pusher block lengthwise of said stretcher bar, and a screw in engagement with said nut and having thereon a journal which is rotatably connected to said frame, and a sleeve on said journal in abutment with a part of said frame, whereby to prevent longitudinal displacement of said screw with relation to said frame.

4. The elements of claim 1, said clamp including a base which is stationary with relation to said frame, vertical standards integral with said frame, a cap movably connected to said standards to co-act with said base, a bridge on said standards and a threaded means for raising and lowering said cap connected to said bridge.

5. The elements of claim 1, said opening being wider than said bar and one or more guides in said opening for reducing the width of said opening to nearly the width of the said stretcher bar, whereby stretcher bars of different widths may be used in said opening, each stretcher bar having a corresponding guide or guides of the requisite width employed therewith, said guides being tapered at their outer ends and said bar being tapered at its inner end, whereby to facilitate the assembling of these parts in said opening.
